US0D1068974S

(12) **United States Design Patent** (10) **Patent No.:** **US D1,068,974 S**
(45) **Date of Patent:** **** Apr. 1, 2025**

(54) **ANKLE WEIGHT**

(71) Applicant: **Huanxiong Xu**, Shenzhen (CN)

(72) Inventor: **Huanxiong Xu**, Shenzhen (CN)

(**) Term: **15 Years**

(21) Appl. No.: **29/955,536**

(22) Filed: **Aug. 1, 2024**

(51) LOC (15) Cl. **21-02**

(52) U.S. Cl.

USPC **D21/683**

(58) **Field of Classification Search**

(57) **CLAIM**

The ornamental design for a ankle weight, as shown and described.

DESCRIPTION

FIG. 1 is a front perspective view of an ankle weight;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines show portions of the ankle weight that form no part of the claimed design.
